UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR SPOONS, &c.

SPECIFICATION forming part of Design No. 28,113, dated January 4, 1898.

Application filed October 25, 1897. Serial No. 656,369. Term of patent 7 years.

To all whom it may concern:

Be it known that I, HENRY L. WALLACE, of Wallingford, in the county of New Haven and State of Connecticut, have invented a new Design for Handles for Spoons, Forks, &c.; and I do hereby declare the following, when taken in connection with the accompanying drawing and the letters of reference marked thereon, to be a full, clear, and exact description of the same, and which said drawing constitutes part of this specification and represents a face view of a spoon embodying my design.

This invention relates to a design for the handles of spoons, forks, and like articles of table-service; and the design consists of the handle, as hereinafter described and shown in the accompanying illustration.

As herein shown, the design consists of a handle for spoons, forks, &c., characterized by a conventionalized border of leaves A and

flowers B of the lilly-of-the-valley, the leaves and blossoms uniting and covering the shank of the handle and gradually diverging, following the contour of the handle, and merging at the tip C in a crowning-point, the border of flowers and leaves inclosing a plain central panel D at the upper end of the handle, all as shown in the accompanying illustration.

I claim—

The design for handles of spoons, forks, and like articles, as herein shown and described.

In testimony whereof I have signed this specification in the presence of two subscribing witnesses.

HENRY L. WALLACE.
